CLAIM

The ornamental design for a manhole bottom plate with
anchors, as shown and described.

DESCRIPTION

FIG. 1 is a perspective view of the bottom of my design;

FIG. 2 is a top view of my design;

FIG. 3 is a side view of my design;

FIG. 4 is an enlarged sectional view of the bottom of my
design;

FIG. 5 is a cross-sectional view along the line 5—5 of FIG.
4; and,

FIG. 6 is a cross-sectional view along the line 6—6 of FIG.
6.

The broken lines showing a pipe is for illustrative purposes
only and forms no part of the claimed design.
